UNITED STATES PATENT OFFICE.

GEORGE EDWARD BLIGH PARKIN, OF TORONTO, CANADA, ASSIGNOR TO
ALEXANDER DOUGLAS FISHER, OF TORONTO, ONTARIO, CANADA.

SCREW-DRIVER.

SPECIFICATION forming part of Letters Patent No. 748,879, dated January 5, 1904.

Application filed March 27, 1903. Serial No. 149,821. (No model.)

To all whom it may concern:

Be it known that I, GEORGE EDWARD BLIGH PARKIN, traveler, a subject of the King of Great Britain, residing in the city of Toronto, in the county of York, in the Province of Ontario, Canada, have invented certain new and useful Improvements in Screw-Drivers, of which the following is a specification.

My invention relates to improvements in screw-drivers; and the object of my invention is to design a device of this class by means of which the screw will be yieldingly held and guided, so that same will be screwed into the wood in a straight position, and to rotate the screw-chamber with the driver, so that the supporting members for the screws will not be bent out of alinement.

The construction and operation of my improved screw-driver will be fully set forth and described in the annexed specification and drawings.

Figure 1 is a general perspective view of my screw-driver. Fig. 2 is a longitudinal section through the chamber, showing construction of same. Fig. 3 is a longitudinal section through the chamber and supporting members used for supporting the screw. Fig. 4 is an end view of the screw-driver, showing the head of the screw supported between the supporting members. Fig. 5 is an enlarged perspective view of one of the supporting members used for supporting the screw.

In the drawings like letters of reference indicate corresponding parts in each figure.

A is the chamber, which is preferably round and is provided with a suitable opening B, by means of which the screws are inserted thereinto. Near the outer end of this chamber the same is cut away on opposite sides, forming opening C, in which operate the supporting ends D of the supporting members E, which are designed to support the screw. Upon referring to the drawings it will be noticed that the supporting members E are secured on the outside of the chamber A, so as to have yielding movement and normally rest parallel therewith.

The preferred form of construction for the supporting ends is as follows: In their normal position the inner edges d of the supporting ends D abut each other. These support-

ing ends are preferably formed integral with the body portions F and are constructed in a curved or hollowed-out manner, as shown at G, so as to offer as little resistance as possible to the screw and to guide same into the passage-way H, formed by the V-shaped grooves I of the said supporting ends. The said grooves need not necessarily be made V-shaped. When the supporting ends are in their normal position, it will be understood that the longitudinal axis of their passage-way H will be on a line with the longitudinal axis of the chamber A. I make the grooves in the supporting ends D of sufficient length so as to hold the screw in position. I preferably construct the sides of the V-shaped grooves I with a suitable taper, so as to better support the screws; but so constructing the said V-shaped grooves is not essential to the operation of this device. The end K of the chamber A extends a short distance beyond the ends of the supporting ends D, so as to prevent said supporting ends from coming in contact with the surface receiving the screw. As shown in the drawings, I preferably secure the ends of the body portions F of the supporting members to the chamber A by means of a suitable ring L, brazed thereto, but of course do not confine myself to this manner of construction of attaching the said supporting members to said chamber.

M is the driving-bar provided with the usual beveled end N, which engages with the screw-head, so as to drive same into the wood. This driving-bar may be of any suitable construction.

From my knowledge of the state of the art I know that there have been springs and spring-held jaws used for supporting the screws; but the means or supporting parts to which the said springs or spring-held jaws are secured do not rotate with the driving-bar. As is well known, the driving end of a screw-driver or a driving-bar is beveled. Consequently by reason of the non-rotation of the supporting parts for the said springs or spring-held jaws the same are forced to spring outward and inward by reason of the action of this beveled end, consequently weakening same. As the beveled sides of the head of the driving-bar come in contact with the said

springs or spring-held jaws same has a tendency to bind against these screw-supporting means, so as to bend them out of alinement. By rotating the chamber A and the supporting members E with the driving-bar M, I entirely prevent any possibility of the beveled end N from bending the said supporting members out of alinement.

I have constructed my device as follows 10 in order to insure the chamber A and its connected parts turning with the driving-bar M. I also preferably construct my device so that the driving-bar cannot be withdrawn from the chamber A. The upper end of the chamber 15 A is flattened on one side, thus providing a stop O, against which a shoulder P, formed on the driving-bar, abuts. The driving-bar is constructed with a flat side Q, so that same may be readily operated within the chamber. 20 This construction of the driving-bar will insure the chamber A turning therewith. It will be understood from Figs. 3 and 4 that the farther the screw is screwed into the wood the wider apart the supporting ends D 25 are forced. As the head of the screw comes in contact with the supporting ends D same are forced apart into the position shown in Fig. 4, and as the end N of the driving-bar passes between said members the same are 30 still farther forced apart, so as to permit the driving-bar to perform its function. The driving-bar is of course provided with any suitable handle R.

As the openings C are only of sufficient 35 size as to permit the supporting ends D to freely operate therethrough, it will be understood that it is most important that the chamber A rotate with the driving-bar M. Were the chamber A held stationary, the action of 40 the beveled end N would bend the supporting members E out of alinement, and thus prevent their operation.

I do not confine myself to the construction 45 shown, by means of which the chamber A is made to rotate with the driving-bar M. It will be further understood that I can construct my screw-driver so that the parts will turn together without necessarily using a stop to prevent the driving-bar from being 50 withdrawn from the chamber A.

I herein claim that I may make such alterations in the construction of my screw-driver that will not depart from the spirit of the invention.

55 What I claim as my invention is—

1. A device of the class described, comprising a chamber provided with a side opening through which the screws are introduced thereinto, and two opposed openings constructed near its outer end so that the end of said chamber will extend beyond the ends of the supporting members for the screw; supporting members, yieldingly secured on the outside of said chamber, and operating 60 within same by means of said openings, so as to hold the screw; a driving-bar operating

within said chamber so as to drive the screw; and means whereby the said driving-bar has only longitudinal movement in said chamber which must rotate therewith.

2. A device of the class described, comprising a chamber provided with a side opening through which the screws are introduced thereinto, and two opposed openings constructed near its outer end so that the end 75 of said chamber will extend beyond the ends of the supporting members for the screw; supporting members, yieldingly secured on the outside of said chamber, and operating within same by means of said openings, so as to hold the screw; a driving-bar operating within said chamber so as to drive the screw; means whereby the said driving-bar has only longitudinal movement in said chamber which must rotate therewith, and means to 80 prevent the driving-bar from being withdrawn from said chamber.

3. A device of the class described, comprising a chamber provided with a side opening through which the screws are introduced 90 thereinto, and two opposed openings constructed near its outer end so that the end of said chamber will extend beyond the ends of the supporting members for the screw; supporting members, yieldingly secured on 95 the outside of said chamber, and operating within same by means of said openings, so as to hold the screw; the supporting ends of said supporting members being provided with slots which, at their inner end, open 100 out in a curved construction G, the said slots together forming a common slot the longitudinal axis of which is on a line with the longitudinal axis of said chamber; a driving-bar operating within said chamber so as to 105 drive the screw, and means whereby the said driving-bar has only longitudinal movement in said chamber which must rotate therewith.

4. A device of the class described, comprising a chamber provided with a side opening through which the screws are introduced thereinto, and two opposed openings constructed near its outer end so that the end 110 of said chamber will extend beyond the ends of the supporting members for the screw; supporting members, yieldingly secured on the outside of said chamber, and operating within same by means of said openings, so as to hold the screw; a driving-bar operating 115 within said chamber so as to drive the screw; the said chamber being constructed with a flattened portion and the said driving-bar being provided with a flat side so as to operate within said chamber and rotate same.

120 5. A device of the class described, comprising a chamber provided with a side opening through which the screws are introduced thereinto, and two opposed openings constructed near its outer end so that the end 130 of said chamber will extend beyond the ends of the supporting members for the screw;

supporting members, yieldingly secured on the outside of said chamber, and operating within same by means of said openings, so as to hold the screw; a driving-bar operating within said chamber so as to drive the screw, the said chamber being constructed with a flattened portion, which forms a stop, and the said driving-bar being provided with a shoulder abutting said stop, one side of said driving-bar being flattened so that it will

only have longitudinal movement within said chamber and rotate same.

In testimony whereof I have signed my name to this specification in the presence of two subscribing witnesses.
